LAWN GROOVING MACHINE

Filed Oct. 30, 1924

Patented Oct. 4, 1927.

1,644,068

UNITED STATES PATENT OFFICE.

DAVID A. McBRIDE, OF ELGIN, ILLINOIS.

LAWN-GROOVING MACHINE.

Application filed October 30, 1924. Serial No. 746,721.

My invention relates to an improved construction of machine for grooving lawns along the edges of side walks, curb stones, etc., in a manner to insure a uniform width 5 and depth of groove so that a pleasing appearance is produced.

My machine consists essentially of a base readily movable along the walk or curb adjacent to which the groove in the lawn is to be made, which base carries a rotary cutter and a motor for driving the same, so that as the machine is moved along the walk or curb the cutter may be revolved at a relatively high speed and, independently of the rate 15 of motion of the machine on the walk or curb, cut the groove in the lawn and at the same time throw the turf and dirt cut from the groove outwardly and away from the groove. My machine is also provided with 20 mechanism for raising the revolvable cutter sufficiently to clear the surface over which the machine is moved, so that the machine may readily be transferred from one location to another without engagement between the 25 cutter and the walk or other surface being passed over by the machine. The adjusting devices also provide a convenient means for determining the depth of the groove that is cut by the machine when in use.

My invention will best be understood by reference to the accompanying drawings showing a preferred embodiment thereof, in which—

Fig. 1 shows the machine in plan view,
Fig. 2 shows the machine in side elevation,

Fig. 3 is a sectional view to an enlarged scale of a part of the machine taken along the line 3—3 in Fig. 1,

Fig. 4 is a bottom view to an enlarged scale of the rear supporting rollers of the machine, and

Fig. 5 is a sectional view of the cutter shaft driving devices, taken along the line 5—5 in Fig. 1.

Similar numerals refer to similar parts throughout the several views.

As shown in Figs. 1 and 2, my machine consists of a base 10 provided with front supporting wheels 11 and 12 and rear supporting wheels 13, 14 and 15 by which the base is supported at a desired distance above the walk or other surface over which the machine is moved. A handle 16 is secured at its forward end to the front end of the base 10 as indicated at 17, and is held in convenient elevated position at its rear end by

braces 18 and 19 which also serve to rigidly secure the rear portion of the handle to the base so that the machine may readily be guided by the handle. 60

The base 10 carries at its rear end in suitable bearings a transversely extending shaft 20 on one end of which a disk 21 is rigidly secured, said disk in turn rigidly supporting a plurality of cutting blades 22 extending 65 radially therefrom. Each of the cutting blades 22 is bent at its outer end to extend substantially parallel with the shaft 20 so that the blades when they are rotated will cut both the side and bottom of the desired 70 groove in the lawn. The blades are preferably made from tempered steel and sharpened to facilitate the cutting operation. The other end of the shaft 20 carries a sprocket wheel 23 engaged by a driving 75 chain 24 which is also in engagement with a sprocket wheel 25 carried by the shaft of a motor 26 suitably supported above the base 10 by a bracket 27. Any suitable type of motor may be used, for example an electric 80 motor or an internal combustion motor. The base 10 and the bracket 27 are preferably made of metal, although I do not limit myself to any particular material in constructing these parts of the machine. Frictional driving engagement is secured between the sprocket wheel 23 and the shaft 20 by a construction shown in sectional view in Fig. 5. This consists of a metal disk 49 85 rigidly secured to said shaft, engaged by a loose disk 50 of fibre or similar material, the other face of which engages a corresponding surface on the sprocket wheel 23, which is otherwise free to turn on the shaft 20. A spring 51 held in compressed condition by a 90 collar 52 on the shaft 20 affords a ready means for producing any desired degree of friction between the disk 50 and the surfaces it engages. In this manner I protect the motor from undue overload if for any reason 95 rotation of the cutting blades is suddenly stopped, by adjusting the driving friction to an amount but slightly in excess of the effort required to cut the turf and dirt from the groove being made, this also serving to 100 reduce the strain on the machine, when, for any reason, its operation is suddenly prevented while the motor is running, for example by the cutting blades striking a stone or other obstruction. 105

Between the disk 21 and the edge of the base 10 I mount a shield and deflector 28

to catch and deflect the dirt and turf cut by the machine and throw them outwardly onto the lawn the edge of which is being grooved. Within the shield 28 I pivotally mount a guide bar 29 on the shield as indicated at 30, so that when the machine is in use the lower end of the guide bar will move along the edge of the walk or curb adjacent which the groove in the lawn is being made, and prevents the revolving cutters from coming in contact with the walk or curb. When the cutter is not being operated and it is desired to move the machine from one location to another, the guide bar 29 may be swung on its pivot to the position indicated in dotted lines at 29^a. I also provide a second guide bar 31 on the front end of the machine, said guide bar being pivotally connected to the edge of the base at 32 and having its upper end pivotally connected by a pitman 33 with a crank 34 rigidly secured to the end of the shaft 20 projecting slightly beyond the disk 21. This construction is desirable to assist in loosening the turf and dirt adjacent the edge of the walk or curb by the rapid vibration of the guide bar 31 as the machine is moved along; the guide bar 31 thus not only serves as a means for properly directing the front end of the machine so that the groove will be properly cut by the revolving cutters, but also serves to cut the dirt and turf along the edge of the walk or curb and thus prepare the same for ready removal by the revolving cutters as the machine is moved along the walk or curb.

The rear supporting wheels 13, 14 and 15 are rigidly secured to a transverse shaft 35 supported in a recess formed therefor in the bottom of the base 10, by bent arms 36, 36 which in turn are rigidly secured to an adjusting shaft 37 mounted in suitable bearings carried by the top of the base 10. The shaft 37 also has rigidly secured thereto an adjusting lever 38 adjacent a segment 39 carried by the base and provided with notches 40 in its edge to receive a latch 41 pivotally connected with the lever 38. The latch 41 is pivotally connected with an operating rod 42 connected at its upper end with an operating member 43 pivotally secured to the lever 38 adjacent the handle 38^a thereof. A spring 44 is provided between the member 43 and the lever 38 to hold the rod 42 and the latch 41 in their lowermost position, thus retaining the latch in any desired one of the notches 40. As a result of the construction just described, when the latch 41 is released from the notches 40, movement of the lever 38 raises or lowers the wheels 13, 14 and 15 as desired so that the rear end of the base and the revolving cutters may either be raised to clear the surface over which the machine is being moved or lowered so that the revolving cutters will cut a desired depth of groove. The relation of the adjusting de-

vices just described is more clearly illustrated in Fig. 3.

When the machine is being used on a walk, to groove the lawn adjacent the edge of the walk, the wheels 11, 13 and 15 are effective in supporting the base in desired position above the surface of the walk, indicated by the broken line 45-45 in Fig. 2, the dividing line between the edge of the walk and the lawn being indicated in Fig. 1 by the broken line 46-46. When it is desired to use the machine to cut a groove in a lawn adjacent a curb, the wheel 12 becomes effective in supporting the front end of the machine and then wheels 14 and 15 serve to support the rear end of the machine in proper position vertically. To provide for using the machine on different widths of curbs, I find it desirable to have the wheel 14 adjustable on the shaft 35 and this is conveniently accomplished by the construction shown in Fig. 4, in which the wheels 13, 14 and 15 are shown as secured to the shaft 35 by means of set screws, although it will be understood that I may use any equivalent retaining devices. All that is required to adjust the wheel 14 to any position relatively to the wheel 15 is to release its set screw and move the wheel 14 longitudinally on the shaft 35 and then tighten its set screw to again secure it to the shaft. As indicated in Fig. 4, a collar 47 is employed on the shaft 35 to prevent longitudinal motion of the shaft through the supporting arms 36, 36.

The end connections of the pitman 33 may conveniently be held in place by split cotter pins or equivalent devices as indicated, facilitating the ready disengagement of the pitman at one of its ends when the machine is to be moved from one location to another without operation of the revolving cutters, for which condition the guide bar 31 may be moved to a horizontal position so as to clear the surface over which the machine is to be moved. A stop pin 48 projects from the shield 28 to retain the guide bar 29 in vertical position when the cutters are in operation as described.

The cutting of edge grooves in lawns along side walks and curb stones is a general practice for the purpose of giving a pleasing appearance to lawns, and with devices heretofore used for accomplishing this purpose it is well known that it has been difficult to secure uniform results both as to the width and depth of these grooves. With my machine the grooves are made of uniform width and depth throughout for any particular setting of the adjusting lever and furthermore as a result of the rapid rotation of the cutting blades, a clean cut edge is made in the lawn at the edge of the groove. In this way a most effective appearance is produced. It will be observed that as a result of the rear guide bar 31 being close to the shaft 20 car-

rying the revolvable cutters, the machine and the cutters may be made to accurately follow the edge of a walk or curb, whatever may be its shape, whether straight or curved in either direction.

While I have shown my invention in the particular embodiment above described, it will be understood that I do not limit myself to this exact construction as I may employ 10 equivalents known to the art at the time of the filing of this application without departing from the scope of the appended claims.

What I claim is:

15 1. In a lawn grooving machine, the combination of a base, wheels carried by said base for supporting it for movement at a desired height above a supporting surface, a rotary grooving cutter carried by said base and 20 adapted to project a desired distance below said supporting surface, a motor carried by said base for driving said cutter, and a guide bar carried by said base for preventing engagement between said cutter and a walk or 25 curb along the edge of which a groove is being made.

2. In a lawn grooving machine, the combination of a base, wheels carried by said base for supporting it for movement at a desired height above a supporting surface, a rotary grooving cutter carried by said base and adapted to project a desired distance below said supporting surface, a motor carried by said base for driving said cutter, a 30 guide bar carried by said base for preventing engagement between said cutter and a walk or curb along the edge of which a groove is being made, said guide bar being adjacent said cutter, a second guide bar in front of 35 said first mentioned guide bar, and means for vibrating said second guide bar by rotation of said motor.

3. In a lawn grooving machine, the combination of a base, wheels carried by said base for supporting it for movement at a desired height above a supporting surface, a rotary grooving cutter carried by said base and adapted to project a desired distance below said supporting surface, a motor carried by said base for driving said cutter, devices for raising and lowering said cutter relatively to said supporting surface as desired, and a guide bar carried by said base for preventing engagement between said cutter and a walk or curb along the edge of which a groove is being made.

4. In a lawn grooving machine, the combination of a base, wheels carried by said base for supporting it for movement at a desired height above a supporting surface, a rotary grooving cutter carried by said base and adapted to project a desired distance below said supporting surface, a motor carried by said base for driving said cutter, devices for raising and lowering said cutter

relatively to said supporting surface as desired, a guide bar carried by said base for preventing engagement between said cutter and a walk or curb along the edge of which a groove is being made, said guide bar being 70 adjacent said cutter, a second guide bar in front of said first mentioned guide bar, and means for vibrating said second guide bar by rotation of said motor.

5. In a lawn grooving machine, the combination of a base, a rotary grooving cutter carried by one end of said base, first supporting wheels secured to said base at its said one end, a motor carried by the other end of said base, driving connections between said motor and said cutter, a second supporting wheel secured to said base at its said other end, a shaft on which said first wheels are mounted, supporting arms extending from said shaft, a pivotal support for said arms carried by said base, a lever secured to said arms to turn them on their support to raise or lower said base as desired, devices for retaining said lever in any desired position, and a deflector for directing material removed from the cut groove away from said groove.

6. In a lawn grooving machine, the combination of a base, a rotary grooving cutter carried by one end of said base, first supporting wheels secured to said base at its said one end, a motor carried by the other end of said base, driving connections between said motor and said cutter, a second supporting wheel secured to said base at its said other end, a shaft on which said first wheels are mounted, supporting arms extending from said shaft, a pivotal support for said arms carried by said base, a lever secured to said arms to turn them on their support to raise or lower said base as desired, and devices for retaining said lever in any desired position, one of said first wheels being movable longitudinally on said shaft depending on the width of supporting surface available to support the machine.

7. In a lawn grooving machine, the combination of a base, a rotary grooving cutter carried by one end of said base, first supporting wheels secured to said base at its said one end, a motor carried by the other end of said base, driving connections between said motor and said cutter, a second supporting wheel secured to said base at its said other end, a shaft on which said first wheels are mounted, supporting arms extending from said shaft, a pivotal support for said arms carried by said base, a lever secured to said arms to turn them on their support to raise or lower said base as desired, devices for retaining said lever in any desired position, and a shield around said cutter having a deflecting surface for directing material removed from the cut groove away from said groove.

8. In a lawn grooving machine, the combination of a base, a rotary grooving cutter carried by one end of said base, first supporting wheels secured to said base at its 5 said one end, a motor carried by the other end of said base, driving connections between said motor and said cutter, a second supporting wheel secured to said base at its 10 said other end, a shaft on which said first wheels are mounted, supporting arms extending from said shaft, a pivotal support for said arms carried by said base, a lever secured to said arms to turn them on their support to raise or lower said base as 15 desired, devices for retaining said lever in any desired position, a guide bar pivotally connected with said base in line with the groove to be cut, a crank rotatable with said cutter, and a pitman connecting said crank and said 20 guide bar to oscillate the latter.
9. In a lawn grooving machine, the combination of a base, a rotary grooving cutter carried by one end of said base, first supporting wheels secured to said base at its 25 said one end, a motor carried by the other end of said base, driving connections between said motor and said cutter, a second supporting wheel secured to said base at its 30 said other end, a shaft on which said first wheels are mounted, supporting arms extending from said shaft, a pivotal support for said arms carried by said base, a lever secured to said arms to turn them on their support to raise or lower said base as 35 desired, devices for retaining said lever in any desired position, and a guide bar connected to the base and extending in use below the 40 surface supporting the machine and movable when not in use above said surface.
10. In a lawn grooving machine, the combination of a base, wheels carried by said base for supporting it for movement at a desired height above a supporting surface, a 45 rotary grooving cutter carried by said base and adapted to project a desired distance below said supporting surface, a motor carried by said base for driving said cutter, and a deflector for directing material removed from the 50 cut groove away from said groove.
11. In a lawn grooving machine, the combination of a base, wheels carried by said base for supporting it for movement at a

desired height above a supporting surface, a rotary grooving cutter carried by said base and adapted to project a desired distance below said supporting surface, a motor carried by said base for driving said cutter, a guide bar carried by said base for preventing engagement between said cutter and a walk or curb along the edge of which a 55 groove is being made, said guide bar being adjacent said cutter, a second guide bar in front of said first mentioned guide bar, means for vibrating said second guide bar by rotation of said motor, and a deflector 60 for directing material removed from the cut 65 groove away from said groove.

12. In a lawn grooving machine, the combination of a base, wheels carried by said base for supporting it for movement at a desired height above a supporting surface, a rotary grooving cutter carried by said base and adapted to project a desired distance below said supporting surface, a motor carried by said base for driving said cutter, and 70 a guide bar carried by said base for preventing engagement between said cutter and a walk or curb along the edge of which a groove is being made, said guide bar being movable when not in use to clear the surface 75 supporting the machine.

13. In a lawn grooving machine, the combination of a base, wheels carried by said base for supporting it for movement at a desired height above a supporting surface, a rotary grooving cutter carried by said base and adapted to project a desired distance below said supporting surface, a motor carried by said base for driving said cutter, a guide bar carried by said base for preventing engagement between said cutter and a walk or curb along the edge of which a groove is being made, said guide bar being adjacent 80 said cutter, a second guide bar in front of said first mentioned guide bar, and means 85 for vibrating said second guide bar by rotation of said motor, said guide bars being movable when not in use to clear the surface 90 supporting the machine.

In witness whereof, I hereunto subscribe 100 my name this 27th day of October, A. D. 1924.

DAVID A. McBRIDE.
